We claim the ornamental design for a bottle, as shown and described.

DESCRIPTION

FIG. 1 is a perspective view of a bottle showing our new design;

FIG. 2 is a front view thereof;

FIG. 3 is a back view thereof;

FIG. 4 is a left side view thereof;

FIG. 5 is right side view thereof; and,

FIG. 6 is a bottom view thereof.

The broken lines in the drawings illustrate the portions of the bottle that form no part of the claim.
